(57) CLAIM

The ornamental design for a beverage can cooler, as shown and described.

DESCRIPTION

FIG. 1 is a perspective view of a beverage can cooler showing my new design;

FIG. 2 is a top plan view thereof;

FIG. 3 is a bottom plan view thereof;

FIG. 4 is a side view thereof. All other sides thereof are substantially identical.

FIG. 5 is a perspective view of an alternate embodiment of FIG. 1;

FIG. 6 is a top plan view of FIG. 5;

FIG. 7 is a bottom plan view of FIG. 5;

FIG. 8 is a side view of FIG. 5. The other sides thereof are substantially identical.

FIG. 9 is a perspective view of an alternate embodiment of FIG. 1;

FIG. 10 is a top plan view of FIG. 9;

FIG. 11 is a bottom plan view of FIG. 1; and,

FIG. 12 is a side view of FIG. 9. The other sides thereof are substantially identical.

The broken lines showing the can are for illustrative purposes only and form no part of the claimed design.
